UNITED STATES PATENT OFFICE

95,457

DESIGN FOR A PAST COMMANDER BADGE OR SIMILAR ARTICLE

Abraham Rosenfield, Boston, Mass.

Application January 11, 1935, Serial No. 54,802

Term of patent 3½ years

To all whom it may concern:

Be it known that I, Abraham Rosenfield, a citizen of the United States, residing at Mattapan (Boston), in the county of Suffolk, State of Massachusetts, have invented a new, original, and ornamental Design for a Past Commander Badge, or Similar Article, of which the following is a specification, reference being had to the accompanying drawing, forming part thereof.

I claim:

The ornamental design for a past commander badge, or similar article, as shown.

ABRAHAM ROSENFIELD.
